UNITED STATES PATENT OFFICE.

CHARLES A. FOSBERG, OF PORTLAND, OREGON.

DRAG SAW.

Application filed April 25, 1921. Serial No. 464,272.

To all whom it may concern:

Be it hereby known that I, CHARLES A. FOSBERG, a citizen of the United States, and resident of Portland, in the county of Multnomah and State of Oregon, have invented 5 a new and useful Drag Saw, of which the following is a specification.

This invention relates more particularly to that class of inventions which are known 10 as drag saws.

The objects of my invention are to provide an exceedingly light saw which is power driven and which is capable of felling trees close to the ground or at some distance above 15 the ground level, and by a slight adjustment is capable of use for "bucking" logs, or sawing them up after the tree is felled. A further object of my invention is to so construct same that the power section may be used as 20 a unit by itself. Another object of my invention is to so distribute the weight that it will not need to be borne entirely or largely by the slide rods, thereby rendering it possible to make same much lighter than is usually 25 the case.

I attain these results in the manner set forth in the following specification and illustrated in the accompanying drawings, in which:

30 Figure 1 is a plan view of the device when used for felling. Figure 2 is a front elevation of same with members 22 and 23 cut away in section and with a portion of a member 52 cut away in section. Figure 3 is a partial bottom view of the saw holding member. Figure 4 is a section along the line 4-4 in Figure 3. Figure 5 is a horizontal section along the line 5-5 in Figure 3. Figure 6 is a front elevation of the power 35 unit with a pulley placed over the driving pinion. Figure 7 is a side elevation of Figure 6. Figure 8 is a section along the line 8-8 in Figure 9. Figure 9 is a section along the line 9-9 in Figure 10. Figure 10 is a plan of Figure 9. Figure 11 is an end elevation of the saw guide showing the usual manner in which a saw blade is guided.

Similar numbers of reference refer to the same or similar parts throughout the several 50 views.

Referring in detail to the drawings I have constructed my device on a somewhat irregular angle plate 10 on whose horizontal portion 11 I have mounted a motor 12, preferably air cooled. This portion 11 has formed on its upper side the two bosses 13 through

which pass the vertical rods 14 provided at their lower ends with the sharpened points 15 and a flange 16.

On the main shaft of the motor 12 is also 60 placed a belt pulley 18 and a bevel pinion 19 whose elongated hub 20 journals in the bearing 21 formed on the vertical portion 22 of the angle plate 10.

Centered on the hub 20 is the faceplate 23 65 from which project the standards 24 between which is mounted in suitable journals 25 and 26 a bevel gear 27 which meshes with the pinion 19. On the shaft 28 is secured a crank arm 29 whose hub is eccentric with 70 the shaft 28. An eccentric strap 30 supports the near ends of the two slide rods 31 whose far ends are joined by the saw guide 32 of the usual type. On the rods 31 I have mounted a crosshead 33 which is joined by 75 means of the connecting rod 34 and the pin 34^A to the crank 29. A web 33^A joins the rod containing portions of the crosshead 33. A flat raised face 35 is also formed on the crosshead 33 and has projecting from its 80 face the two pins 36 arranged to engage suitable holes in the saw 37 when its toothed edge 38 is turned in either direction.

Between the pins 36 is placed the head 39 of the T-bolt 40, one end of which rests upon 85 the saw 37 and extends slightly beyond the line of the pins 36, and the other end drops into a recess in the face 35. The bolt 40 passes through the hub 41 and is equipped with a hand nut 42 by means of which the 90 saw 37 may be securely clamped against the face 35.

An arched arm 43 is hinged to lugs on the journals 25 and 26 and has riveted thereto a pair of angle irons 44 between whose swinging ends is hinged a dog 45 provided with a point 46 and a projecting lug 47 to facilitate the withdrawing of the point 46 from the tree 48. A wedge 49 may be slipped between the dog 45 and the angle iron 44 after 100 the dog 45 has been driven home, thereby crowding the angle irons 44 against the tree. Also hinged to the lug on the journal 25 is a tubular brace 50 which is provided with a dog 51 adapted to be driven into the tree 105 on the side opposite the dog 45.

In order that the torque of the motor shaft will not cause the motor and its parts to rotate about the axis of the shaft 28, I have secured a flat plate member 52 between the standards 24 and to the face plate 23. The plate 52 is curved to permit con-

siderable rotation of the parts on the center of the pins 53. On the rear of the member 43, as is best shown in Figure 9, I have formed the projecting lugs 54 and 55. The 5 lower lug 55 extends some distance underneath the curved edge of the plate 52. Through the upper lug 54 I have passed a pipe 56 which rests on a clamp 57, which in turn, rests upon the plate 52 and the 10 lug 55 at the other end. A bolt 58 is now passed downwardly through the pipe 56 and the clamp 57 and the lug 55 below which is placed the nut 59 on the bolt 58.

It will be evident that any pressure applied to the bolt 58 will be transmitted through the pipe 56 and tend to clamp the members 43 and 52 together. In order to use the saw in a plane at right angles to the one just described it is only necessary 20 to release the clamps 60 on the members 22 and 23 and swing the entire saw to the desired angle and reclamp same in that position.

By supporting the member 10 on a block 25 61 and placing the pulley 62 over the pinion 19 and securing same with the bolt 63, the power section of the saw may be used independently of the saw itself.

While I have thus illustrated and described my invention it is not my intention to limit myself to this precise construction but intend that it shall cover all forms and modifications that fall fairly within the appended claims.

35 What I claim as new is:

1. In a drag saw, the combination of a supporting frame, a housing rotatably carried by said frame, a motor on said frame whose shaft is concentric with the axis of 40 rotation of said housing, a bevel pinion on said motor shaft, a bevel gear in said hous-

ing meshing with said pinion, a shaft journaling in said housing and carrying said bevel gear, a crank having an eccentric hub mounted on said bevel gear shaft, a pair 45 of slide rods secured at one end to said eccentric, a saw guide joining the far end of said rods, a saw carrying crosshead on said slide rods, a connecting rod joining said crank to said crosshead, a pair of dog-carrying braces hinged on said housing and means for locking the relation of said braces to said housing.

2. A drag saw having a motor, a ground engaging frame supporting said motor, a 55 rotatable housing mounted on said frame, a bevel gear mounted in said housing, a pinion on the motor shaft engaging said gear, a crank driven by said bevel gear, an arched frame hinged to said housing, dog carrying 60 braces joined to said arched frame, clamp means for locking said arched member to said rotatable housing, an eccentric driven by said bevel gear, a slideway mounted at one end on said eccentric, a crosshead on 65 said slideway, a connecting rod joining said crosshead to said crank, and means for attaching said crosshead to a saw.

3. In a drag saw, the combination of a 70 rotatable housing, an arched frame hinged on said housing, a plate attached to said housing, a clamping means on said arched frame for securing same to said plate consisting of a pair of lugs, one of which forms a table against which bears said plate, a clamp resting upon said plate and upon said 75 table, a pipe passing through the remaining lug and resting upon said clamp, a bolt passing through said lugs, pipe and clamp and a hand nut on said bolt.

CHARLES A. FOSBERG.
